UNITED STATES PATENT OFFICE.

OSCAR A. PEDERSEN, OF NEW YORK, N. Y.

ROOFING TILE.

Application filed April 15, 1921. Serial No. 461,599.

To all whom it may concern:

Be it known that I, OSCAR A. PEDERSEN, a citizen of the United States, and a resident of the city of New York, borough of the 5 Bronx, county and State of New York, have invented certain new and useful Improvements in Roofing Tiles, of which the following is a full, clear, and exact description.

Among the principal objects which the 10 present invention has in view are: to avoid breakage of the tile in service and in handling; to form runways for water; to provide means incorporated in the structure for aligning the tile; to conceal the junction of 15 the tiles in the separate courses; to avoid leakage; and to provide a means for anchoring the tile in service relation.

Drawings.

20 Figure 1 is a top plan view of a fragment of a roofing tile, constructed and arranged in accordance with the present invention;

Figure 2 is a cross section thereof, the section being taken on the line 2—2 in 25 Figure 1;

Figure 3 is a sectional view, the section being taken as on the line 3—3 in Figure 1, and showing in conjunction therewith by dotted lines the relation of an adjacent tile;

30 Figure 4 is a perspective view of a tile constructed and arranged in accordance with the present invention.

Description.

35 Tile, when shaped as shown in the drawings, are constructed from cement concrete, which is molded to form lengthwise grooves 9, 10 and 11. The grooves 9 and 10 form runways for moisture falling on or accumulated on a roof covered by said tile. The 40 grooves 11 are for aligning the adjacent tile. Each tile is provided at one end with the grooves 11, and at the opposite end, or the overhang 12 of the tile itself, with ridges 45 13, which register with and fit into the grooves 11. As will be seen in the drawings, the grooves 11 are so shaped that the ridges 13 do not secure the said grooves to the bottom thereof. By this construction

50 small auxiliary drainage grooves are formed, which will carry off any water or moisture which escapes the main grooves 9 and 10, or passes under the edge of the adjacent tile.

55 As seen best in Figures 3 and 4, the tile is hollow beneath to form pairs of aligned

recesses 14, one on each side of the planes of the opposite side edges formed by the drainage groove 11. By forming the recesses 14 the structure of the tile is lightened 60 without weakening the same. Further service is rendered by providing air spaces beneath the tile and between the same and the sheathing on which it is usually mounted.

Intermediate the ends of the tile cross 65 ridges 15 are provided to interrupt the continuity of the recesses 14, whereby to form the pairs of the latter, as above stated. Piercing the cross ridges 15 are perforations 16, designed to receive a tying member such 70 as the wire which is passed around the sheathing or convenient element of the structure for securing the tile in place.

From the foregoing it will be seen that 75 a roof constructed and arranged in accordance with the present invention is light and strong, and so arranged that side drifting of water such as deposited on the roof by rain, is prevented, and that in consequence the water is evenly delivered throughout 80 the roof to the drainage gutter with which the same is furnished.

Claims.

1. A roofing tile comprising a hardened 85 body formed to provide a drainage groove extending longitudinally of its upper face and recesses in its lower face formed in pairs one on each side of the planes of the opposite side edges formed by said drainage 90 groove, one side edge of the tile being formed to provide an overhanging portion having ridges extending longitudinally of its under face, the other of the side edges having its upper face formed to provide grooves adapted 95 to receive in interlocked engagement therewith the ridges of the overhanging portion of an adjacent tile, and a thickened portion formed between the oppositely disposed recesses and extending transversely 100 beneath the said drainage groove to add strength to the tile in its entirety.

2. A roofing tile comprising a hardened body formed to provide a drainage groove extending on the longitudinal center of its 105 upper face and recesses in its lower face formed in pairs one on each side of the planes of the opposite side edges formed by said drainage groove, one of the longitudinal side edges of the tile being formed 110 to provide an overhanging portion having ridges extending in spaced parallel relation

on its under face, the other of the longitudinal side edges of the tile having its upper face formed to provide grooves adapted to receive in interlocked engagement therewith the ridges of the overhanging portion of an adjacent tile, and a thickened portion formed between the oppositely disposed recesses and extending transversely beneath the said drainage groove in a manner to add 10 strength to the tile in its entirety.

3. A roofing tile comprising a hardened body formed to provide a drainage groove extending on the longitudinal center of its upper face and recesses in its lower face 15 formed in pairs on each side of the planes of the opposite side edges formed by said drainage groove, one of the longitudinal side

edges of the tile being formed to provide an overhanging portion having ridges extending in spaced parallel relation lengthwise of its under face, the other of the longitudinal side edges having its upper face formed to provide grooves adapted to receive in interlocked engagement therewith the ridges of the overhanging portion of an adjacent tile, the portions of the tile disposed between the adjacent ends of the recesses of each pair of recesses having openings therethrough for the insertion and passage of tying members whereby each tile 25 of a course of such tiles will be securely held in service.

OSCAR A. PEDERSEN.
